UNITED STATES PATENT OFFICE.

FREDERICK LEOPOLD, JR., OF HARMONVILLE, AND ROLLIN JEFFERSON LIMBERT, OF CONSHOHOCKEN, PENNSYLVANIA, ASSIGNEES TO LEE RUBBER & TIRE CORPORATION, OF CONSHOHOCKEN, PENNSYLVANIA, A CORPORATION OF PENNSYLVANIA.

EXPANSION BAR.

Application filed July 10, 1926. Serial No. 121,722.

Our invention relates to new and useful improvements in expansion bars and more particularly to expansion bars that are adapted for expanding and gripping paper shells, fabric rolls, cores, or in fact any article in the form of a roll or bolt that has a hollow center, in which a bar or shaft of this type may be inserted.

One of the objects of the present invention is to provide an expansion bar or shaft, which consists of a core, and a plurality of longitudinally extending keys, and the parts so arranged that when the keys are moved forwardly, they also move radially to grip whatever is about the said bar.

Still another object of the invention is to provide a bar with a small revolvable head that is connected with radially expanding keys so that a rotation of the head either expands or contracts the keys, depending on the direction in which the head is revolved.

Still another object of the invention is to provide an expansion bar with a sleeve or collar just beyond the head, so that the bar may be readily held in an aligned position when it is desired to rotate the material and the bar.

Still another object of the invention is to provide an expansion bar consisting of but few parts which may be readily assembled and readily operated when so assembled.

With these and other objects in view, the invention consists in certain new and novel arrangements and combination of parts as will be hereinafter more fully described and pointed out in the claim.

Referring now to the drawings, showing a preferred embodiment of our invention,

Fig. 1 is a sectional view taken throughout the bar and to pass through two of the keys in their normal or contracted position.

Fig. 2 is a similar view, but with the head moved forwardly and the keys in their radially expanded position.

Fig. 3 is a side elevation of the end of the block in which the core is threaded and pinned.

Fig. 4 is an end view of the same.

Fig. 5 is a section taken on line 5—5 of Fig. 1, the section being slightly irregular to show the three keys and key ways or grooves.

Fig. 6 is a view in detail of the core, two of the keys and a split ring.

Fig. 7 is a sectional view similar to Fig. 5 and taken on line 7—7 of Fig. 1.

Fig. 8 is a similar view taken on line 8—8 of Fig. 2.

Fig. 9 is a similar sectional view taken on line 9—9 of Fig. 1, and

Fig. 10 is a perspective of two of the keys showing their relative position to each other that they will assume when in the core.

Referring now more particularly to the several views, we have shown the preferred type or form of expansion bar as consisting of a core 1 externally threaded at its one end as at 2, while extending nearly throughout the length of this core are the three slots or grooves 3, for the purpose of holding the gripping keys which will be shortly explained.

This core 1 is preferably made of circular steel stock and when the grooves are formed, lengthwise of the bar, and at different points around its periphery, the bottom of the grooves are cut or fashioned with the raised portions 4 and intermediate valleys 5, as may be clearly seen in the several views, especially in Fig. 6.

Near the outer end of the core 1 there is cut a circumferential slot 6, while a further similar slot 7 is shown near the opposite end of the core, both of which slots receive split rings as will be shortly mentioned.

Formed on the core and adjacent the threaded end, is the circular integral sleeve 8, as may be seen in Fig. 6, so that on this sleeve may be placed a bushing or housing 28 to support the bar as a whole in position when assembled.

Referring now to the several keys 9, and inasmuch as they are all alike, a description of one will be a description of all. As may be seen in Figs. 6 and 10, each key consists preferably of a steel bar, the upper and lower edges of which are both irregular, the upper edge being slotted to receive the split rings and fit within the support 28 while the lower surface is provided with an indentation or a valley 10 about midway of its length and the one end is reduced as at 11, thereby leaving the ridge or projection 12, as may be seen in the several views. As heretofore mentioned, the upper edge of the bar is provided with slots or cut out portions, one being shown as at 13, and in a like manner, at 14. In making the last men-

tioned cut, however, a small lug 15 is left standing, thus forming a small indentation between the lug and the shoulder 16. The one end of the key is provided with a short 5 stub or foot 17 which extends into the means for advancing the keys as will be shortly mentioned. These three keys are then placed within the slots or grooves 3, and in their normal position they will nest within the 10 grooves of the core, as the several ridges will project within the valleys 10, and the expansion bar will of course be in its normal or contracted position.

For holding the keys within the groove, 15 there are shown two split rings 18, which are placed about the heretofore mentioned slots 6 and 7 of the core, and about the slots formed in the keys, and as the keys expand, (move radially) of course, the rings will 20 open only to retract again when the keys are contracted.

Referring now to the nut or head 19, which is the means for advancing and retracting the keys 9 within the slot, and which action 25 radially expands or contracts the keys, it will be seen that this head is internally bored and threaded as at 20, while a small chamber 21 is formed in one face thereof over which face there is shown a plate 22 30 which in turn is held in position by the screws 23. This plate is also internally or centrally bored, and fitting within this chamber, as may be seen in Fig. 1, are the inner ends of the stubs or feet 17 of the keys, 35 after which the plate is locked in position, thus securing the keys with relation to the head.

The diameter of the chamber and the diameter of the opening within the plate 22 is 40 such, however, that when the keys are moved forwardly from the position shown in Fig. 1, to the position shown in Fig. 2, the feet or inner end of the keys may expand or move outwardly to the edge of this chamber.

45 Referring now to Figs. 1 and 2, we have shown the threaded end 2 of the core 1 extending within a block 24, over which block there is placed a collar 25, while a key 26 is shown as passing through the collar block 50 and core 1 for holding the core from revolving with relation to the block and collar.

Fitted within the periphery of the nut or head 19 are the little knurled handles 27 that are to be gripped when it is desired to 55 revolve the head on the core 1 to move the keys forwardly and rearwardly.

About the sleeve 8, there is shown a bushing 28, provided with a flange 29, which flange may be fastened to a wall, partition, 60 or other means to support or hold the expandible bar when the same is in use.

It might here be mentioned that the block 24 and core 1 must be held against rotation when it is desired to move the keys by rotating the head 19 but after an article has been 65

gripped on the expansion bar, the bar may be held in any manner so that it may revolve as a whole and act as a shaft for the article that is held on the bar.

Referring now to the manner of operating 70 the bar, it will be seen that it is only necessary to revolve the head 19 in a forward direction, the block 24 with the core 1, of course, being held against rotation. This turning of the head on the core will cause 75 the three keys to move forwardly and will force the ridges of the keys upon the ridges formed in the bottom of the grooves and the keys will then expand radially and assume the positions illustrated in Fig. 2, the expanding of these keys thus holding any shell or core (within certain diameters) that have been placed on the expansion bar. The article will be held until the head is revolved again in a reverse direction when the keys, 80 of course, will again nestle tightly within the grooves of the core. The tension of the split ring will hold the parts tightly together, and of course, will prevent the keys from dropping out of the several grooves. 85

It will be understood that although we have shown three keys, a greater or lesser number might be used, although we have found that three keys arranged as shown are sufficient.

It will also be understood that we have not shown the supports or bearings for the opposite ends of the expansion bar, but these will be arranged to suit the different conditions, it being understood that it is 100 necessary that the block 24 be held against movement when it is desired to rotate the head to manipulate the keys and at all other times the expansion bar and head may revolve in its entirety without in any way expanding or contracting the keys. 105

In the drawings we have shown the expansion bar as relatively short in length, but it is to be understood that it may be of any length desired, it being only necessary to 110 provide a longer core and longer keys, both of the parts, of course, being provided with the necessary ridges and valleys to radially expand the keys as they are moved in the core.

We have found in actual use that the bars will serve the purpose for which they are intended; are easily expanded and contracted, and call for little repairs or adjustments.

Many slight changes might be made without in any way departing from the spirit and scope of the invention.

Having thus described our invention, what we claim as new and desire to secure by Letters Patent is:

An expansion bar comprising a rod in the form of a core having one end externally threaded, a block, said core threaded with in said block and pinned to the same, a head internally threaded on said threaded 120

portion of the core and adapted to move forwardly and rearwardly on said core, the said core provided with a plurality of longitudinally extending grooves or keyways, and a plurality of ridges formed in the bottom surfaces of said grooves, a plurality of keys having uneven bottom edges and having their one ends mounted in said revolvable head, means encircling the keys and core for holding the keys within said groove, means

for mounting the expandible bar, a rotation of the head in one direction adapted to provide a wedging action between the keys and the core to radially move said keys and said head locking the keys longitudinally of the core.

In testimony whereof we affix our signatures.

FREDERICK LEOPOLD, JR.
ROLLIN JEFFERSON LIMBERT
